US00D777757S

(12) **United States Design Patent** (10) Patent No.: **US D777,757 S**
 Kisseelev et al. (45) Date of Patent: ** Jan. 31, 2017

(54) **DISPLAY SCREEN WITH GRAPHICAL USER INTERFACE**

(71) Applicant: **Microsoft Corporation**, Redmond, WA (US)

(72) Inventors: **Sergey Kisseelev**, Woodinville, WA (US); **Harold Gomez**, Seattle, WA (US)

(73) Assignee: **Microsoft Corporation**, Redmond, WA (US)

(**) Term: **15 Years**

(21) Appl. No.: **29/534,305**

(22) Filed: **Jul. 28, 2015**

(51) LOC (10) Cl. **14-04**

(52) U.S. Cl.

USPC **D14/486**

(58) **Field of Classification Search**

USPC D14/485-495
